US00D943182S

(12) **United States Design Patent** (10) Patent No.: **US D943,182 S**
(45) Date of Patent: ** Feb. 8, 2022

(54) **AEROSOL GENERATING STICK**

(71) Applicant: **Philip Morris Products S.A.**,
Neuchâtel (CH)

(72) Inventors: **Gerard Zuber**, Froideville (CH);
Daniele Sanna, Marin-Epagnier (CH);
Gianluca Sechi, Colombier (CH)

(73) Assignee: **Philip Morris Products S.A.**,
Neuchâtel (CH)

(**) Term: **15 Years**

(21) Appl. No.: **29/762,876**

(22) Filed: **Dec. 18, 2020**

(57) **CLAIM**

The ornamental design for an aerosol generating stick, as
shown and described.

DESCRIPTION

FIG. 1 is a right side perspective view of an aerosol
generating stick;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a left side perspective view thereof.

The broken lines in the drawings depict portions of the
aerosol generating stick that form no part of the claimed
design.

1 Claim, 8 Drawing Sheets
